United States Patent Office

Des. 215,380
Patented Sept. 23, 1969

215,380

CHECK-OUT COUNTER OR SIMILAR ARTICLE

William E. Kinslow, Willingboro, N.J., assignor to Radio
Corporation of America, a corporation of Delaware

Filed Oct. 14, 1968, Ser. No. 13,986

Term of patent 14 years

Int. Cl. D6—01

U.S. Cl. D80—2

Fig. 4.Fig. 5.Fig. 6.

FIGURE 1 is a perspective view of a check-out counter or similar article showing my new design;

FIGURE 2 is a top plan view thereof;

FIGURE 3 is an elevational view taken from the left side thereof;

FIGURE 4 is an elevational view taken from the right side thereof;

FIGURE 5 is a rear elevational view thereof; and

FIGURE 6 is a front elevational view thereof.

I claim:

The ornamental design for a check-out counter or similar article, substantially as shown.
